UNITED STATES PATENT OFFICE.

DANIEL L. CHANDLER, OF AYER, MASSACHUSETTS, ASSIGNOR TO
GEORGE J. BURNS, OF AYER, MASSACHUSETTS.

PLANER.

No. 826,476.

Specification of Letters Patent.

Patented July 17, 1906.

Application filed April 14, 1904. Serial No. 203,145.

To all whom it may concern:

Be it known that I, DANIEL L. CHANDLER, of Ayer, in the county of Middlesex and State of Massachusetts, have invented certain new and useful Improvements in Planers, of which the following is a specification.

This invention relates to planers; and its object is to increase the speed of operation of machines of this class in order to handle a greater quantity of work in a given time. That object is accomplished, first, by the provision of improved means for accelerating the platen on its return or non-cutting stroke. Of late years in order to keep pace with the improvement in quality and durability of planing-tools a demand has arisen for a cutting speed in planers higher than the maximum of from twenty to thirty feet per second, which is now considered practicable; but the difficulty encountered in speeding up the cutting stroke of the platen has been that the return or non-cutting stroke would have to be initiated at a correspondingly slower speed, and hence there would be no net gain, the reason for this being that the work of converting the forward or cutting stroke into the return stroke is represented by the combined inertia of the two strokes. Accordingly a return stroke of about two and one-half times the speed of the cutting stroke has been about the limit of safety, beyond which an excessive strain would be placed upon the parts, to resist which would be to make them of prohibitive size and cost. I have found that this ratio can be greatly exceeded by initiating the return stroke of the platen at some such speed as that required by the old ratio, then accelerating the platen to a higher speed, then retarding it under positive control to the slower return speed at which it was started, and then reversing it onto the cutting stroke. By this method of acceleration and positive retardation I avoid imposing on the mechanism which drives the platen any considerable strains greater than have heretofore been imposed and greater than can be safely borne without undue increase in the size or cost of the driving mechanism, provided such mechanism is properly constructed.

I furthermore provide an improved feed mechanism for imparting the feed to the cutting-tool, whereby the operator may quickly

adjust the tool by hand when this is necessary, particularly in "backing out," and also an improved mechanism for varying the length of feed of the cutting-tool while the machine is running.

Of the accompanying drawings, Figure 1 represents a plan view of the platen, belt-shifting devices, and connected parts of a planer constructed according to my invention. Fig. 2 represents a right-hand side elevation of the middle portion of the planer. Fig. 3 represents a transverse vertical section. Figs. 4 to 7, inclusive, represent side elevations showing the trip mechanism in four different positions. Fig. 8 represents a detail side elevation showing one of the trip-dogs elevated out of operative position.

The same reference characters indicate the same parts in all the figures.

In the drawings, 20 is the reciprocating platen adapted to hold the work and mounted on the usual guides. Said platen is driven by a main drive-shaft 21, having a pinion 22, meshing with a gear 23 on the left-hand side of the planer-bed, said gear being attached to a counter-shaft 24, having a pinion 25, meshing with a gear 26, supported in bearings mounted on the planer-bed frame, which engages a rack 27, Fig. 3, on the under side of the platen.

On the right-hand side of the planer the shaft 21 carries a fast pulley 28, flanked by two loose pulleys 29 30 of equal size therewith, and on the left-hand side this shaft carries a fast pulley 31, flanked by a loose pulley 32 of equal size. The pulley 28 receives motion from two belts, one of which (the belt 33) imparts the forward or cutting stroke to the platen through the medium of the gearing described, while the other belt 34 imparts the slow return movement to the platen at the beginning and end of the non-cutting stroke. A belt 35 on the opposite side of the machine when working on the fast pulley 31 imparts the quick return movement to the platen.

The belts 33 34 are engaged, respectively, by belt-shifters 36 37, pivoted on fixed studs 38 39 and having studs 40 41 on their short arms, Fig. 1, working in the slot of a segmental cam 42, pivoted on fixed stud 43. The belt 35 is engaged by a belt-shifter 44, pivoted on a fixed stud 45 and having on its short arm a stud 46, working in the slot of a laterally-

sliding cam 47. The cams 42 and 47 are connected across by a link 48.

A link 49, pivoted to the cam 42, connects the latter with a bell-crank-shaped trip-lever 50, pivoted to the side of the planer-bed 51. This lever carries a stud 52, adapted to be engaged by dogs on the platen 20 at opposite ends of the latter's stroke.

53 is an inclined dog on the platen adapted 10 to lift the stud 52, throwing off the cutting-belt and throwing on the slow-return belt, the said dog operating at the end of the cutting stroke of the platen toward the right as viewed in Figs. 4 to 7.

54 is a second dog, inclined in the opposite direction to the dog 53 and adapted to still further lift the stud 52, said dog 54 operating shortly after the commencement of the return stroke and serving to throw off the slow-20 return belt and throw on the quick-return belt. The dog 54 is mounted on a vertical slide 55, so that during the latter part of the cutting stroke of the platen toward the right the stud 52 may lift the dog 54 and the latter will drop 25 back into position to encounter the stud 52 after the commencement of the return stroke. The dogs 53 54 are mounted upon a common support 56, adjustable lengthwise of the platen by bolt 57 and slot 58 after the usual manner 30 of the belt-shifting dogs on planers, whereby the length of stroke of the platen is determined.

59 is a prop pivoted to the support 56 and adapted to engage the slide 55 and hold the 35 same in an elevated position, as shown in Fig. 8, when it is desired to throw the dog 54 out of the platen of stud 52 and make the quick-return belt inoperative—as, for example, on short work.

40 60 is a dog adapted to encounter the stud 52 near the completion of the return stroke and throw the quick-return belt off and the slow-return belt on.

61 is a dog which encounters the stud 52 at 45 the termination of the return stroke and reverses the platen from slow-return to cutting stroke.

The dogs 60 61 are formed on a support 62, adjustable lengthwise of the platen by means 50 of bolts 63 in the slot 58.

When the platen 20 is finishing the cutting stroke, it will be understood that the cams 42 47 are in the opposite extreme of their movement from that shown in Fig. 1. The stud 55 40 of the belt-shifter 36 for the cutting-belt 43 is then in a non-concentric portion 64 of the groove of cam 42, and the stud 41 of the slow-return-belt shifter 37 is in a concentric portion 65 of the cam-groove. The stud 46 60 for the quick-return-belt shifter 44 is in the parallel portion 66 of the groove of cam 47. The cutting-belt will therefore be the only one in operation at this time. The stud 52 of trip-lever 50 has its most depressed position, as represented in Fig. 4, and is about 65

to ride up on the dog 33. By doing so the trip-lever 50 is thrown to the position shown in Fig. 5, causing the stud 40 to occupy a concentric portion 67 of the slot of cam 42 and the stud 41 to occupy an eccentric portion 68 of the cam-slot, whereby the cutting-belt is thrown off of the tight pulley 28 by belt-shifter 36 and the slow-return belt is thrown onto said pulley by the belt-shifter 37. The stud 46 remains in the parallel part 75 66 of the slot of cam 47. By the reversal of motion of the planer-bed on its return or non-cutting movement the stud 52 is thrown up by the dog 54 and the cams 42 47 thereby 80 moved to their extreme position. (Represented in Fig. 1.) The stud 41 rides into a concentric portion 69 of the slot of cam 42 from the eccentric portion 68 of said slot and the stud 46 into an inclined portion 70 of the slot of cam 47, which throws the slow-return belt 85 from the fast pulley 28 to the loose pulley 30, and the quick-return belt from the loose pulley 32 to the fast pulley 31. The platen thereby receives an accelerated movement and returns at its maximum speed until dog 60 encounters 90 stud 52. By reversal of the last-described foregoing movement this operation throws the quick-return belt from the fast pulley 31 to the loose pulley 32 and the slow-return belt from the loose pulley 30 to the fast pulley 28. 95 It will be observed that the platen 20 is thereby positively connected with its slow-speed driving device or belt 34. The speed of the platen is thereby reduced through an intermediate stage before reversing onto the 100 cutting stroke, which is accomplished by the dog 61 encountering stud 52 and effecting a shifting of the parts the reverse of that effected by dog 53, the slow-speed-return belt being shifted from fast pulley 28 to loose pulley 30 and the cutting-belt shifted from loose pulley 29 to fast pulley 28. In the figures of the drawings the trip-dogs 53 54 are for compactness of illustration shown much 105 nearer to the dogs 60 61 than they would 110 usually be in practice.

It will be observed that the several driving-belts are successively and automatically brought into exclusive and positive driving connection with the platen—that is, each belt 115 has positive control of the platen when in position and also exclusive control, the other belts being then out of operative position.

71 is the cross-feed saddle carrying the cutting-tool 72 and fed by a screw 73, journaled in the vertically-adjustable beam 74 and operating in a nut on the cutter-saddle in the usual manner. On the end of screw 73 is a pinion 75, meshing with a gear 76, to which is fixed a toothed ratchet-wheel 77. Heretofore this ratchet-wheel has usually been fed step by step by an ordinary pawl yieldingly in contact with the ratchet. With such a construction when it becomes necessary to "back out" the tool 72 by hand—that is, 120 125 130

move it in a direction contrary to the feed—by fitting a crank to the squared end of the screw 73 the operator has been required to lift the pawl and rotate the crank and screw, the operation being a somewhat difficult and time-consuming one and usually requiring the operator's two hands to perform it; but by the improved construction now to be described I avoid the difficult operation heretofore required and allow the power-feed to be released and the tool backed out with one hand. On the sleeve 78, to which the gear 76 and ratchet 77 are fixed, is mounted a pawl-support 79, having a split hub 80 frictionally embracing the sleeve 78.

81, Fig. 2, is the usual cross-feed rack operated by link 82, lever 83, and link 84 on a wrist 85 on the friction-collar 86 embracing a drum 87 on the shaft 24. The rack 81 meshes with a pinion on a short shaft 89, carried by the beam 74. On the outer end of this shaft is affixed an arm or finger 90, adapted to engage heels or projections 91 on the shafts of two oppositely-acting pawls 92, pivoted to the friction-support 79. These pawls have substantially radial noses engaging the teeth of ratchet 77 and are provided with projections 93, connected by a spring 94, which tends to throw the pawls out of engagement with the teeth of the ratchet. Eccentrics are provided for disabling either pawl and allowing the other pawl to feed the tool in the direction desired. The rack 81 receiving motion from friction-collar 86 oscillates the finger 90, which engages the operative pawl and throws it into engagement with the ratchet 77 and feeds said ratchet a distance depending upon the length of stroke of the rack, the friction of support 79 on collar 78 being such as to permit this action to take place. On the back stroke of finger 90 it encounters the heel-piece 91 of the inoperative pawl and relieves the strain on the operative pawl, whereupon the spring 94 retracts the latter from engagement with ratchet 77, and the support 79 is retracted for a fresh operative stroke. It will be seen that the operative pawl 92 is under strain only at the moment of feed. This strain may be relieved at any time it is desired by the operator to feed by hand by applying the hand-crank to screw 73 and giving the latter a slight "kick" ahead merely sufficient to relieve the friction between ratchet 77 and pawl 92, whereupon the pawl will be automatically released from engagement with the ratchet by the action of its spring 94, and the tool will be thereby freed from the automatic feed and may be fed by hand in either direction. Inertia and recoil will also in most cases be sufficient to relieve the pawl immediately after its feeding movement.

96 is a shaft on beam 74, splined to gearing in the saddle 71 in the usual manner, whereby a vertical feed is imparted to the tool 72

upon removing the pinion 75 and substituting a pinion on shaft 96 to mesh with gear 76. It will be understood, therefore, that my improvement applies to the vertical or other feed of the tool, at well as to the horizontal feed thereof.

The friction of collar 86 on its drum 87 is furnished by a spring. The collar is opened at each end of its stroke to relieve this friction by a cam-strut operating between the limbs of the collar and having an arm 100 alternately engaging two pins 101 102 as the drum is oscillated to and fro. I mount the pin 102 upon a hand-lever 103, adjustable about the axis of shaft 24 and having a locking-pin 104 at its upper end, adapted to engage any one of a segment of holes 105 105 formed in the side of the planer-bed. By the foregoing arrangement while the planer is running the operator may adjust the stroke of rack 81, and hence the length of the cross-feed movement at each reciprocation of the planer-platen from nothing to a maximum by swinging the lever 103 so as to bring its pin 102 nearer to or farther from the fixed pin 101.

I claim—

1. In a planer, the combination of a bed, a reciprocating platen, slow-speed forward and reverse acting devices located on one side and a high-speed reverse-acting device located on the opposite side of the bed, a pivoted cam connected to operate said slow-speed devices, a reciprocating sliding cam connected to operate said high-speed device, a connection extending across the planer joining said cams to communicate motion from one to the other and mechanism operated by the platen for operating said cams to alternately throw into and out of gear the said devices.

2. In a planer, the combination of a reciprocating platen, devices for imparting a forward movement and a plural-speed reverse movement thereto, a trip member controlling said devices, a dog on the platen acting on said trip member to move the same at the end of the forward stroke of the platen, a second dog acting directly on said trip member at the beginning of the return stroke of the platen and displaceable from operative position by said trip member on the forward movement of the platen, and means for acting on said trip member at the end of the return movement of the platen.

3. In a planer, the combination of a reciprocating platen, devices for imparting a forward movement and a plural-speed reverse movement thereto, a trip member controlling said devices, a dog on the platen acting on said trip member at the end of the forward stroke of the platen, a second dog acting on said member at the beginning of the return stroke thereof and displaceable bodily from operative position by said trip member on

the forward movement of the platen, and means for acting on said trip member at the end of the reverse movement of the platen.

4. In a planer, the combination of a reciprocatory platen, devices for imparting a forward movement and a plural-speed reverse movement thereto, a trip member controlling said devices, a dog on the platen acting on said trip member at the end of the forward stroke of the platen to move the trip member a limited distance in one direction, a second dog comprising a slide-displaceable bodily from operative position by said trip member on the forward movement of the platen, and operative at the beginning of the return stroke thereof to move the trip member farther in the same direction, and means for acting on said trip member at the end of the reverse movement of the platen to move the member in the opposite direction.

5. In a planer, the combination of a reciprocatory platen, devices for imparting a forward movement and a plural-speed reverse movement thereto, a trip member controlling said devices, a dog on the platen having an inclined surface arranged to engage said trip member at the end of the forward stroke of the platen, a guideway connected to said dog, a second dog slidably mounted in said guideway and having a reversely-inclined surface arranged to engage the trip member at the beginning of the reverse stroke of the platen, the said inclined surfaces of the dogs being adapted to move the trip member successive distances in one and the same direction, and means for acting on said trip member at the end of the reverse movement of the platen to move the member in the opposite direction.

40 6. In a planer, the combination of a reciprocatory platen, devices for imparting a forward movement and a plural-speed return movement thereto, a trip member controlling said devices, a dog on the platen having an inclined surface arranged to engage and move said trip member at the end of the forward stroke of the platen, a second dog slidably mounted adjacent the first dog provided with a projecting rib formed on its opposite sides with correspondingly-inclined surfaces and arranged to be engaged by the trip member at the end of the forward stroke

of the platen and be displaced thereby, said dog being further arranged to resume its former position after passing said trip member and to engage the same with the inclined upper surface of said rib at the beginning of the return movement of the platen, said dogs being adapted to move the trip member successive distances in one and the same direction, and means for acting on said trip member at the end of the return movement of the platen to move the member in the opposite direction.

7. In a planer, the combination of a reciprocatory platen, driving devices for imparting a forward movement and a plural-speed return movement thereto, a trip member consisting of a bell-crank lever having a substantially vertical arm connected to operate by its movement said devices and a substantially horizontal arm provided with a lateral projection, a stationary and a vertically-slidable dog carried by the platen, each having a cam projection arranged at a level to engage the lateral projection of the trip member, the cam projection on the fixed dog being inclined to raise the trip-member projection at the conclusion of the forward movement of the platen to cause a reversal of the driving devices, the cam projection on the slidable dog being inclined to that on the fixed dog and having lower and upper surfaces, the former arranged to engage the trip-member projection and raise the dog clear of said projection during the forward movement of the platen, and the latter to extend beneath said projection at the beginning of the return movement of the platen and raise the horizontal arm of the trip member a further amount, the cam projection of said slidable dog being adapted to drop into place behind the trip-member projection after passing by the same on the forward movement of the platen, and means for acting on said trip-member projection at the end of the return movement of the platen to move the projection downward.

In testimony whereof I have affixed my signature in presence of two witnesses.

DANIEL L. CHANDLER.
